CLAIM

We claim the ornamental design for a closure for a container, as shown and described.

DESCRIPTION

FIG. 1 is a top perspective view of an embodiment of the claimed design;

FIG. 2 is another top perspective view of the claimed design of FIG. 1;

FIG. 3 is a top plan view of the claimed design of FIG. 1;

FIG. 4 is a bottom plan view of the claimed design of FIG. 1; FIG. 5 is a first elevation view of the claimed design of FIG. 1; and,

FIG. 6 is a second elevation view of the claimed design of FIG. 1.

The ornamental design which is claimed is shown in solid lines in the drawings. The broken lines in the drawings are included for the purpose of illustrating subject matter that forms no part of the claimed design.
